HEAT-TREATING APPARATUS

Kenneth L. Scott, Western Springs, Ill., assignor
to Western Electric Company, Incorporated,
New York, N. Y., a corporation of New York

Application December 13, 1941, Serial No. 422,783

4 Claims. (Cl. 266—5)

This invention relates to a heat treating apparatus and more particularly to an apparatus for heat treating metals.

In the heat treatment of some types of magnets, it is necessary to control the rate of cooling within a limited range in order to produce the desired magnetic properties. One method of cooling has been to place the heated magnets in an insulated chamber. However, in this method, the initial cooling of the heated magnets occurs at a very rapid rate because of the absorption of heat by the insulation when it is first exposed to the magnets. In producing some types of magnets, it is necessary to have a comparatively slow rate of initial cooling.

An object of this invention is to provide an effective and efficient heat treating apparatus.

In accordance with the object, one embodiment of the invention contemplates a chamber having walls of anodized aluminum and a base of the same material.

Other objects and advantages will be apparent from the following detailed description taken in conjunction with the following drawing, wherein:

Fig. 1 is a side elevation of one embodiment of the invention,

Fig. 2 is a plan view of the same,

Fig. 3 is an end elevation of the same.

In one method employed in the manufacture of magnets composed of iron, nickel, aluminum, cobalt and copper, it is necessary to heat the magnets to a temperature of about 2100° Fahrenheit. Then, in order to produce the desired magnetic qualities, it is necessary to cool the magnets at a substantially uniform rate. Satisfactory results have been obtained where the magnets have been permitted to cool to 1100° Fahrenheit, in approximately 4½ minutes. In order to achieve a uniform rate of cooling, numerous methods have been employed heretofore with varying success. In one method, the magnets were placed in an insulated chamber. However, a sudden initial drop in temperature is caused by the absorption of heat by the insulation and then, as the insulation becomes warm, the rate of cooling becomes quite slow. This extreme variation in the rate of cooling is undesirable. In another method, cooling has been thermostatically controlled by placing the magnets in a thermostatically controlled oven. This method, however, is expensive.

To overcome these difficulties, in accordance with this invention, a chamber is employed having a heat reflecting lining which will utilize the heat radiated by the articles to be cooled to retard cooling and to effect a uniform rate of cooling.

A reflector material was required which would be highly efficient while, at the same time, relatively inert to the effect of the heat radiated by the magnets. Anodized aluminum is such a material. Anodizing the aluminum gives a reflector surface which is efficient and, at the same time, 60

durable. Tests have shown that untreated aluminum rapidly oxidizes when exposed to the heat of the magnets and this oxidation causes a discoloration of the surface of the aluminum with resultant loss of reflector efficiency. The anodized aluminum, on the other hand, does not discolor and maintains its efficiency over a long period of use.

Referring now in detail to the construction shown in Figs. 1 to 3 inclusive, the heat treating chamber comprises a removable cover 10 of anodized sheet aluminum of suitable thickness. A handle 11 has been provided for convenience in removing the cover 10. A base 12 comprises a sheet of anodized aluminum and the cover 10 is simply placed on the base 12. Also resting on the base 12 is a removable rack 14 supported by six posts 13 of suitable material. A removable tray 15, which is formed of an open mesh material and contains magnets 16, is supported by the rack 14. Open mesh, metallic material is used in the tray to increase the area of effective radiation of the objects supported thereby.

In the operation of this embodiment of the invention, the tray containing the magnets is removed from the furnace, wherein the magnets have been heated to the required temperature. The tray is then placed on the rack which rests on the base plate, as shown in Figs. 1 and 3, and the cover is placed over the tray and rests on the base plate. Thus, the magnets are completely surrounded by walls of anodized aluminum and very effective reflection of the heat radiated by the magnets is achieved. The result is that the magnets cool at a substantially uniform rate. The speed of cooling approximates the optimum rate but if necessary the cover may be removed from time to time to increase the rate of cooling.

It will be understood that the nature and embodiment of the invention herein described is merely illustrative and that many changes and modifications may be made therein without departing from the spirit and scope of the invention.

What is claimed is:

45. 1. In an apparatus for heat treating articles, a lining of anodized aluminum for controlling the cooling rate of the articles therein.

2. In an apparatus for heat treating articles, means for reflecting heat radiated by the articles therein comprising a lining of anodized aluminum.

3. In an apparatus used in the heat treatment of magnetic articles, means for providing a substantially uniform rate of cooling by reflecting heat radiated by the articles therein comprising a lining of anodized aluminum.

55. 4. An apparatus for heat treating articles comprising a chamber having a surface of anodized aluminum for reflecting heat to the articles.

KENNETH L. SCOTT.
